UNITED STATES PATENT OFFICE.

CHESTER HUNT, OF LYNN, MASSACHUSETTS, ASSIGNOR TO UNITED SHOE MACHINERY CORPORATION, OF PATERSON, NEW JERSEY, A CORPORATION OF NEW JERSEY.

MACHINE FOR LAYING AND ROLLING QUARTER LININGS.

Application filed March 18, 1922. Serial No. 544,951.

To all whom it may concern:

Be it known that I, CHESTER HUNT, a citizen of the United States, residing at Lynn, in the county of Essex and State of Massachusetts, have invented certain Improvements in Machines for Laying and Rolling Quarter Linings, of which the following description, in connection with the accompanying drawings, is a specification, like reference characters on the drawings indicating like parts in the several figures.

This invention relates to a device for use in the manufacture of vulcanized footwear and is herein illustrated as embodied in a device for holding the partially assembled upper of an arctic overshoe during the laying of the quarter lining and for pressing the laid lining into place.

In the manufacture of arctic overshoes, commonly called arctics, it is customary to build the upper complete off the last and then to assemble it together with an insole upon a last and proceed to complete its manufacture. In order to promote brevity and clearness, certain steps in the manufacture of a high arctic such as a four-buckle arctic will be considered. In the manufacture of a high arctic the parts of the upper except the quarter lining are put together and rolled or otherwise pressed to force the parts into firm adhesion. Then the upper, thus far made, is closed by sewing together the rear edges of the quarters. The incomplete upper, wrong side out, is then placed over a form having the general shape of the rear portion of a last, the incomplete upper being so placed upon the form that the back seam is uppermost and the unlined quarters exposed. The quarter lining is now laid on the inside surface of the quarters and rolled. The form hitherto used has been a solid wooden member and the rolling has been done by a single hand roller.

Under these conditions, the laying of the lining has been accomplished with difficulty by reason of the fact that the operator must use one hand most of the time to hold the upper in proper position upon the form whereas it is very desirable that the operator have both hands free to manipulate the lining. And with regard to the rolling of the lining, this has involved difficulty for the same general reason namely that no means was provided for holding the upper upon the form, and for the further reason

that hand rolling is an extremely laborious operation.

According to one feature of the invention, means are provided for holding the upper firmly in place. The illustrative device comprises a properly shaped horn and a movable member adapted to draw the rear portion of the upper about the horn and hold the upper firmly in place. This leaves both hands of the operator free to lay the lining and greatly facilitates this operation.

According to another feature of the invention, pressing means are provided which may be operated after the lining has been laid in place. In the illustrative device a series of spring-pressed rollers arranged in a circular pattern are mounted in a carrier which may be moved back and forth to cause the rollers to traverse that portion of the upper which is supported on the horn. With this construction, the rolling operation is made much easier and much more effective.

Referring now to the accompanying drawings:

Figure 1 is a side elevation, with certain parts shown in section, of a machine in which the present invention is embodied; and

Figure 2 is an end elevation.

Bolted to a bench or table 3 is a plate 5 having rising therefrom a standard 7; and bolted at one end to the standard is a horn 9 which overhangs the table. This horn is designed to support the rear portion of a closed upper; and its operative surface has the general shape of the rear portion of a last. The horn carries on its inner wall near one end thereof a guide 11 in the form of a U-shaped member, the base of the U being vertical. Slidably mounted on the base of the U is an eye 13 carried by a movable member 15. Extending through bores in the lower ends of arms 17 which are bolted to and depend from the upper wall of the horn 9 is a rod 19 attached at one end by a tension spring 21 to one end of the horn and at the other by a cord 23 to a treadle 25, the cord passing over pulleys 27 journaled in the standard 7. Fast to the rod 19 are two sleeves 29, and pivoted to these sleeves are the upper ends of links 31, the lower ends of the links being pivoted to brackets which are bolted to the movable member 15. With this construction, when

110

the treadle is depressed, as shown, the rod 19 is pulled toward the standard 7 and the member 15 is moved downwardly away from the horn 9, its eye 13 sliding upon the upper right base of the U 11.

In using this device in the manufacture of an arctic overshoe, the closed upper of the arctic, substantially complete except for the quarter lining, is placed over the horn with the back seam resting upon the top of the horn. The treadle is then depressed, whereupon the member 15 is moved downwardly away from the horn thereby engaging the front portion of the upper and drawing the rear portion thereof smoothly about the horn. In order to permit the operator to maintain the upper thus held without keeping his foot on the treadle, the treadle is provided with a pawl 35 which projects from the side of the treadle and may be caused to engage one or another of notches cut in the adjoining side of a small stationary upright 37. After the device has been expanded and locked in expanded condition with the rear portion of the upper drawn smoothly about the horn, the operator lays the quarter lining in proper position.

It is necessary that the lining be pressed firmly against the quarter of the upper so as to expel any entrapped air and to bring the parts into firm adhesion, it being understood that that surface of the lining which is next to the quarter is tacky by reason of the presence of unvulcanized rubber, and that if any air remains entrapped between the parts, it will cause blisters in the subsequent vulcanizing operation. In order to press the lining against the quarter of the upper for the purposes indicated above, the following construction is provided.

Fast to the table 3 at each side of the horn 9 are guides 39 to receive rolls 41, said rolls being rotatably mounted at the lower portion of a circular carrier 43. This carrier is provided with a circular guideway on its inner face in which is mounted a circular frame 45 having attached to it two handles 47. Mounted on the frame 45 in spaced relation and alternately on one side and on the other are a series of pressers in the form of rollers 49. Each roller is rotatably mounted in the arms of a fork 51 the stem 53 of which extends through a bore in a boss on the frame 45. A compression spring 55 surrounds each stem 53 as shown; and on the outer end of each stem is threaded an adjusting nut 57 which determines the normal position of each roller. Normally, that is when the carrier 43 occupies its inoperative position as shown in the figures, the rollers are arranged in a substantially circular pattern. As soon, however, as the operator has grasped the handles 47 and pulled the carrier forward so as to cause

the rollers to run over the upper upon the horn 9, the pattern of the rollers changes to conform to the transverse curvature of the horn at the particular locality engaged at any moment by the rollers. And at any time the operator may rotate the frame 45 in one direction or the other to bring some one or more of the rollers into contact with any locality which the operator sees is not being properly rolled. In order that, when the carrier 43 is pulled to the left as viewed in Figure 1, the rollers may ride upon the horn without difficulty the edge of the standard 7 is beveled upwardly as indicated at 59.

Although the invention has been set forth as embodied in a particular machine, it should be understood that the invention is not limited in the scope of its application to the particular machine which has been shown and described.

Having thus described my invention, what I claim as new and desire to secure by Letters Patent of the United States is:

1. A machine for operating upon the closed, unlasted upper of a shoe having, in combination, a horn over which the upper may be placed with its rear portion resting upon the horn, the shape of the horn conforming in general to that of the rear portion of a last, a member adapted to engage the upper at a locality spaced from the horn, means for moving the member away from the horn to draw the upper about the horn and hold it from movement with respect thereto, and means for applying pressure to that portion of the upper which is supported by the horn.

2. A machine for operating upon the closed, unlasted upper of a shoe having, in combination, a horn over which the upper may be placed with its rear portion resting upon the horn, the shape of the horn conforming in general to that of the rear portion of a last, a member adapted to engage the upper at a locality spaced from the horn, operator controlled means for moving the member away from the horn to draw the upper about the horn and hold it from movement with respect thereto, and means for applying pressure to that portion of the upper which is supported by the horn.

3. A machine for operating upon the closed, unlasted upper of a shoe having, in combination, a horn over which the upper may be placed with its rear portion resting upon the horn, the shape of the horn conforming in general to that of the rear portion of a last, a member adapted to engage the upper at a locality spaced from the horn, operator controlled means for moving the member away from the horn and for temporarily locking the member, and means for applying pressure to that portion of the upper which is supported by the horn.

4. A machine for operating upon the

- closed unlasted upper of a shoe having, in combination, a horn over which the upper may be placed with the back seam uppermost, a member adapted to engage the upper at a locality spaced from the horn, yielding means for holding the member in proximity to the horn to permit the upper to be placed over the horn and member, operator controlled means for moving the member away from the horn to draw the rear portion of the upper about the horn, and means for applying pressure to that portion of the upper which is supported by the horn.
- 5 5. A machine for operating upon the closed, partially completed upper of a shoe of the vulcanized type, comprising a horn having substantially the shape of the rear portion of a last, a movable member, yielding means for holding the member in proximity to the horn to permit the closed upper to be placed over the horn and member with the back seam uppermost and resting upon the horn, a slide bearing for the member, 10 treadle controlled means for moving the member away from the horn to draw the rear portion of the upper about the horn, and means for applying pressure to that portion of the upper which is supported by the horn.
- 20 6. A machine of the class described having, in combination, a horn for supporting the rear portion of the unlasted upper of a shoe, a carrier, guideways for the carrier extending lengthwise of the horn, said carrier being shaped to extend around the supporting surface of the horn, and a plurality of individually yielding pressers mounted in the carrier.
- 25 7. A machine of the class described having, in combination, a horn for supporting the rear portion of the unlasted upper of a shoe, a carrier, guideways for the carrier extending lengthwise of the horn, said carrier being shaped to extend around the supporting surface of the horn, and a plurality of individually yielding pressers mounted in the carrier, the pressers being arranged in overlapping relation so as to be effective on 30 all portions of the upper supported by the horn.
- 40 8. A machine of the class described having, in combination, a horn for supporting the rear portion of the unlasted upper of a shoe, means for stretching said rear portion over said horn, a carrier movable with respect to the horn, a plurality of rollers mounted in the carrier and arranged in such manner that they will traverse substantially all of that part of the upper which
- is supported on the horn, and yielding means for urging the rollers toward the horn.
- 45 9. A machine of the class described having, in combination, a horn for supporting the rear portion of the unlasted upper of a shoe, means for stretching said portion over said horn, a carrier movable lengthwise of the horn, a plurality of rollers mounted in the carrier and arranged in such manner that they will traverse substantially all of that part of the upper which is supported on the horn and yielding means one for each roller for urging the rollers toward the horn.
- 50 10. A machine of the class described having, in combination, a horn for supporting an unlasted upper, a carrier movable lengthwise of the horn, a curved guideway in the carrier, a curved frame mounted for angular movement in the guideway, and a plurality of pressers mounted in the frame.
- 55 11. A machine of the class described having, in combination, a horn for supporting an unlasted upper, a carrier movable lengthwise of the horn, a circular guideway in the carrier, a frame mounted for angular movement in a path the plane of which is transverse to the lengthwise dimension of the horn in the guideway, and a plurality of pressers mounted in the frame.
- 60 12. A machine of the class described having, in combination, a horn for supporting an unlasted upper, a carrier movable lengthwise of the horn, a curved guideway in the carrier, a curved frame mounted for angular movement in the guideway, and a plurality of yielding pressers mounted in the frame.
- 65 13. A machine of the class described having, in combination, a horn for supporting an unlasted upper, a carrier movable lengthwise of the horn, a circular guideway in the carrier, a frame mounted for angular movement in the guideway, and a plurality of yielding pressers mounted in the frame.
- 70 14. A machine of the class described having, in combination, a form for supporting the rear portion of an unlasted upper, means for holding the upper on the form, a carrier movable lengthwise of the form, said carrier being provided with a circular guideway, a frame mounted in the guideway, a plurality of individually yielding presser rollers mounted in the frame, and a handle fast to the frame whereby the carrier may be moved back and forth lengthwise of the form and the frame may be oscillated in a path the plane of which is transverse to the length dimension of the form.
- 75 15. In testimony whereof I have signed my name to this specification.
